Primary Examiner — Terry Wallace(74) *Attorney, Agent, or Firm* — Lowe Graham Jones PLLC(57) **CLAIM**

I claim the ornamental design for the canning funnel, as shown and described.

DESCRIPTION

FIG. 1 is a perspective view of a canning funnel, showing my new design.

FIG. 2 is a front view of the canning funnel.

FIG. 3 is a right side view of the canning funnel, the left side view being a mirror image.

FIG. 4 is a back view of the canning funnel; and,

FIG. 5 is a top view of the canning funnel.

The bottom view not visible in the drawings is unornamented and forms no part of the claimed invention. Features illustrated in broken lines form no part of the claimed invention.
